United States Patent Office.

S. R. WILMOT, OF BRIDGEPORT, CONNECTICUT.

Letters Patent No. 85,047, dated December 15, 1868.

IMPROVEMENT IN LAMP-CHIMNEYS.

The Schedule referred to in these Letters Patent and making part of the same.

To all whom it may concern:

Be it known that I, S. R. WILMOT, of Bridgeport, in the county of Fairfield, and State of Connecticut, have invented a new Improvement in Manufacture of Lamp-Chimneys; and I do hereby declare the following, when taken in connection with the accompanying drawings, and the letters of reference marked thereon, to be a full, clear, and exact description of the same, and which said drawings constitute part of this specification, and represent, in

Figure 1, a side view, and in

Figure 2, a section on line *xx*.

This invention relates to an improvement in the manufacture of lamp-chimneys, the result being the production of chimneys, the bases of which are all precisely a given size.

To produce chimneys of this description, I employ a machine of my invention, application for patent for which was allowed, October 22, 1868; and

The invention consists in a chimney, the base of which is fluted or corrugated in the process of manufacture, which said flutes or corrugations indicate the process by which the chimney was sized, and thus form a mark whereby the chimneys may be designated or recognized.

In order to the clear understanding of my invention, I will fully describe the same, as illustrated in the accompanying drawings.

The chimney A is first formed in the usual manner, then placed upon the machine before referred to, the base setting over the several fingers, which, when the chimney is so set, are caused to expand, each finger striking respectively upon the chimney at *a*, forming a ridge or indentation at that point, the space between falling into the shape of a flute or corrugation. The fingers all expanding to a given size, the chimneys are produced of a like even size.

It may be proper here to remark that the result is accomplished alike by the expansion of the fingers within the chimney, or by contraction without.

The importance of constructing chimneys with their bases all of a given size, will be readily recognized, and especially so in that class of chimneys which are designed for what are termed and known to the trade as "sun-burners."

Having fully described my invention, What I claim as new and useful, and desire to secure by Letters Patent, is—

As an article of manufacture, lamp-chimneys, fluted or corrugated at the base, substantially in the manner and for the purpose herein set forth.

S. R. WILMOT.
